BENNET HOTCHKISS AND SAMUEL C. GOODSELL, OF NEW HAVEN,
CONNECTICUT.

Letters Patent No. 63,160, dated March 26, 1867.

IMPROVEMENT IN ORE-CRUSHERS.

The Schedule referred to in these Letters Patent and making part of the same.

TO ALL WHOM IT MAY CONCERN:

Be it known that we, BENNET HOTCHKISS and SAMUEL C. GOODSELL, of New Haven, in the county of New Haven, and State of Connecticut, have invented new and useful improvements in Machines for Pulverizing Quartz; and we do hereby declare the following, when taken in connection with the accompanying drawings, and the letters of reference marked thereon, to be a full, clear, and exact description of the same; and which said drawings constitute part of this specification, and represent, in—

Figure 1, a front view.

Figure 2, a side view.

Figure 3, a top view.

Figure 4, a vertical central section.

Our invention relates to an improvement in machines for pulverizing quartz and other ores; and consists, first, in a mechanism for converting rotary into reciprocating motion; second, in the construction of the box which contains and the hammer which pulverizes the quartz, and tube communicating therewith, so as to automatically feed the lumps to be pulverized and discharge the same when pulverized.

To enable others skilled in the art to construct and use our improvement, we will proceed to fully describe the same as illustrated in the accompanying drawings.

A is the bed, B a frame which supports the hammer C and its operative mechanism, and is adjustably fixed to the bed A. The hammer C is fixed to a bar, D, which moves freely up and down in guides E; F is the driving-shaft supported on the frame B, and so as to revolve freely in bearings G. The said shaft between its two bearings G G is formed into two cranks I I', (see fig. 3,) each of which is connected to the bar D of the hammer by flexible cords or straps, L and L', which pass between pulleys N and N'; the cord L' passing down is secured to the bar D at a, the other cord L passing up and secured to the bar D at b, as seen in fig. 4. O is a cast-iron box set into the bed A, as seen in fig. 4, resting upon an elastic substance or spring P, or its equivalent. Within the said box O I place the hammering block R, and insert through the said box, as seen in figs. 1 and 2, two tubes, S and T; the tube T being used to introduce the pieces or lumps of quartz to be crushed, and the tube S to conduct the pulverized quartz from the box as hereafter described. The hammer C should nearly fill the box O by piston rings or otherwise; as seen in fig. 4, so that as it descends it will force air into the box to create a blast sufficient to blow the powdered quartz out through the tube S, and as the hammer rises other pieces or lumps will enter through the tube T beneath the hammer on to the block R to be pulverized. The tube S should be made the proper length in proportion to the blast created by the descent of the hammer, and is set perpendicular, its top turned outward or not as required, so that the heavier or not fully pulverized particles will fall back into the box, while that which is sufficiently pulverized will pass out with the air. When the driving-shaft is made to revolve from the position denoted in fig. 4 the cranks I' will cause the hammer C to rise until the crank I' has attained the position opposite in the circle which it describes, or relatively, as that of the crank I, while the crank I will advance towards the hammer to allow the hammer to draw up the strap L connected thereto, until the said crank I has attained the relative position of the crank I'. At this point the hammer is raised to the position denoted in red, fig. 4. The cranks continuing their revolution, the crank I will draw the hammer down while the crank I' will in its turn release its power upon the hammer to permit its descent and when rapidly revolving. The power thus added to the hammer in its descent is in proportion as the velocity of the crank is greater than the natural gravity of the hammer. As by this construction the descent of the hammer is to a positive point, it is necessary that some adjustment should be introduced to provide for the variation in the size of the lumps inserted beneath the hammer. As the lumps may to a certain extent be regulated before their introduction, a slight adjustment only is needed for this purpose. I introduce an elastic substance or spring P beneath the box O; this may be of steel springs, rubber, or any equivalent therefor which will allow the box O to be slightly depressed and cause it again to resume its natural position. This arrangement will fully compensate for the slight variation which may exist in the lumps as prepared for the pulverizing. Another adjustment is required to allow the insertion of lumps of a larger size. (It is designed that the lumps shall be graded so that at one time the lumps of nearly the same size may be placed in the box and another time lumps of another

nearly regular size.) For this purpose a screw, W, is inserted through the frame B into the bed A, which by being turned, (here represented as turned by means of a worm, X,) will raise or lower the frame as the case may be, and the frame secured to the bed by means of the bolt Y. This arrangement is fully shown in fig. 4. It now remains to describe the clutch by which we connect or disconnect the power which drives the machine. On the shaft F I fix a plate, d, as seen in fig. 3, on the said shaft, and beside the said plate d I place a driving-pulley, f, so as to revolve freely thereon. I form the side of the pulley next to the plate d to correspond to the form of the said plate, be it flat, conical, concave, or convex, preferring a conical form as seen in fig. 3. Power is applied to the pulley f in the usual manner. By pressing the said pulley f firmly against the plate d, the pulley revolving so that the friction between the two will cause the plate and the shaft to which it is attached to revolve with it, by releasing the pressure upon the said pulley the power will be disconnected and the operation of the hammer be arrested at the completion of each revolution. My arrangement for pressing the pulley against the plate as seen in figs. 1, 2, and 3: e is a spring, one end of which bears upon the hub of the pulley as seen in fig. 3, the other end secured to some part of the machine. From said spring e a cord or its equivalent h is attached to the treadle m, so that by placing the foot upon the treadle m the spring will be borne against the pulley, pressing it against the plate d with sufficient force to cause it to revolve as before described. Removing the foot from the treadle the power will be disconnected. By varying the pressure upon the pulley so as to lessen or increase the friction, the velocity of the driving-shaft may be increased or decreased at the pleasure of the operator. We do not wish to be understood as confining ourselves to this particular description of clutch or pulley, as in many cases a common pulley may be fixed to the driving-shaft to impart a constant motion to the hammer. This is desirable after the quartz has been broken, that is, when pulverizing, or, if preferred, and in many cases it would be desirable, that both a fixed pulley and the clutch pulley should be applied, in which case a loose pulley should also be attached in such relation to the fixed pulley that the band may be shifted from one to the other as required, in such manner as any person skilled in the use of machinery will readily understand.

We have entitled our invention a "machine for pulverizing quartz," and have described it as for that purpose, but we do not wish to be understood as limiting our invention to such purpose, as the mechanism which we describe for operating the hammer may be used for operating hammers for various purposes.

We do not broadly claim an outlet and inlet tube in pulverizing machines.

Having therefore thus fully described our invention, what we claim as new and useful, and desire to secure by Letters Patent, is—

1. The shaft F with double-crank I I, straps L and L', hammer C, box O, when constructed and arranged to operate together substantially as described.
2. The tubes S and T when constructed as described and used in connection with box O, for the purposes substantially as specified.
3. Controlling the force and rapidity of the blows of the hammer by means of the treadle m, cord h, spring e, pulley f, and plate d, when operating as and for the purposes set forth.

BENNET HOTCHKISS,
SAM'L C. GOODSELL.
